SUBMERSIBLE BELL FOR LIFTING SUBMERGED OBJECTS

Ralph T. Best, Canton, Ohio

Application February 16, 1951, Serial No. 211,250

3 Claims. (Cl. 114—53)

1

This invention relates to pontoons for raising submerged objects, and more particularly to a submersible, bell-type pontoon.

It is among the objects of the invention to provide an improved pontoon of the bell type having an open bottom, so that it can be easily submerged to a location adjacent the object to be raised, and can be easily filled or partly filled with air to cause it to rise in water in which it has been submerged; which is so constructed that a number of the pontoons can be nested together, one within the other, to save storage space; which includes a detachable reinforcing structure that can be removed when the pontoons are nested together for storage; which may include means for attaching it to the side of a submerged ship or boat hull; and which is strong and durable in construction, economical to manufacture and easy to transport and use.

Other objects and advantages will become apparent from a consideration of the following description and the appended claims in conjunction with the accompanying drawings, wherein:

Figure 1 is a side elevational view of a pontoon illustrative of the invention shown attached to the side of a ship hull diagrammatically illustrated in cross-section;

Figure 2 is a view similar to Figure 1, but with the pontoon shown in lifting position and having parts broken away and shown in cross-section to better illustrate the construction thereof;

Figure 3 is a top plan view of the pontoon illustrated in Figures 1 and 2;

Figure 4 is a fragmentary cross-sectional view on an enlarged scale on the line 4—4 of Figure 3;

Figure 5 is a cross-sectional view on the line 5—5 of Figure 4;

Figure 6 is a side elevational view of a somewhat modified form of pontoon;

Figure 7 is a fragmentary cross-sectional view on an enlarged scale on the line 7—7 of Figure 6;

Figure 8 is a transverse cross-sectional view on the line 8—8 of Figure 7;

Figure 9 is a fragmentary cross-sectional view on an enlarged scale on the line 9—9 of Figure 8;

Figure 10 is a fragmentary cross-sectional view on an enlarged scale on the line 10—10 of Figure 7; and

Figure 11 is a fragmentary cross-sectional view similar to Figure 7, but showing a number of pontoons nested together for storage.

With continued reference to the drawings, and particularly to the form of the invention shown in Figures 1 to 5, inclusive, the pontoon therein illustrated comprises a hollow body 10 of substantially square cross-sectional shape and having a length greater than its maximum, transverse dimension. This body has a side wall which may be formed of four pieces 10a, 10b, 10c and 10d, of suitable sheet material, such as boiler plate, welded or otherwise secured together along abutting edges to provide a body of square or rectangular cross-sectional shape. One end of the body is

2

open, and a flat end wall 11 closes the other end of the side wall of the body. This end wall has a substantially perpendicularly extending marginal flange 12 which is disposed within the side wall 11 of the body at the corresponding end of the latter and welded or otherwise permanently secured to the side wall plates. The end wall may also comprise a piece of boiler plate of suitable thickness having the flange 12 upset thereon. The end wall or plate 11 is disposed somewhat inwardly of the adjacent ends of the side wall plate, as particularly illustrated in Figures 1 and 2, to provide a protective rim or flange 13 projecting outwardly of the end wall.

15 A cable attaching eye 14 is secured to the end wall 11 and projects outwardly of the outer side of 11 and projects outwardly of the outer side of the end wall for attaching one end of a cable 15 to the pontoon for raising and lowering the pontoon, and a manually operated valve 16 is secured in the end wall 11 at a location spaced from the eye 14 for controlling the flow of air out of the hollow body of the pontoon.

The body 10 is tapered from its open end to 25 its closed end, so that a number of these hollow pontoon bodies can be nested together for convenience in storage and transportation, and can be removed, one at a time, from their nested condition, as used.

30 A reinforcing structure 17 surrounds the side wall of the body at the larger, open end of the body, and, in this form of the invention, may comprise four lengths of channel iron disposed with the outer sides of their web portions against the outer sides of the side wall plates of the body, and with one flange flush with the edges of the corresponding side wall plates at the open end of the body. These lengths of channel iron are welded together at their abutting ends and are 35

40 also welded to the side wall plates to permanently secure the reinforcing structure to the open end of the body. Angular gusset plates 18 are secured to the reinforcing structure at the corners thereof by suitable means, such as rivets 19, to further reinforce the structure and to prevent distortion of the shape of the open end of the pontoon body.

45 Apertured lugs 20 are secured to one of the channel iron members at spaced apart locations 50 along such member and are disposed between and substantially perpendicular to the flanges of the member to which they are secured.

Suitable strands, such as the chains 21, are secured one to each of the lugs 20, each chain being secured at one end to the corresponding lug and extending therefrom.

55 A channel iron guide 22 extends medially of the outer side of the end wall 11 from the side wall plate 10c adjacent the lugs 20 to the opposite side wall plate 10a and is disposed substantially perpendicular to these side wall plates. This guide is firmly secured, as by welding, to the end wall and to the side wall plates at its opposite

end, and has its open side facing another of the side wall plates of the body. The side wall plate 10c adjacent the lugs 20 is apertured at the adjacent end of the guide 22, and a bar 23 of square or rectangular cross-sectional shape is extended through the aperture 24 in the side wall plate 10c and is slidably received in the guide 22. The bar 23 and the web of the guide 22 are provided with apertures which are in registry at various predetermined positions of the bar longitudinally of the guide, and bolts 25 extend through the registering apertures in the bar and the guide to secure the bar to the guide in selected positions of longitudinal adjustment relative thereto.

The end of the bar 23 projecting outwardly of the apertured side wall plate 10c is pointed, as indicated at 26, and adjacent this pointed end the bar is provided with a transversely extending slot 27 and with mutually registering apertures in its portions at respectively opposite sides of the slot.

An arm 28 extends through the slot 27 in the bar 23 and is provided at its mid-length location with a laterally projecting apertured lug or eye formation 29 and a pivot pin 30 extends through the apertures in the bar and through the apertured eye formation 29 to pivotally secure the arm at its mid-length location to the bar 23. At its opposite ends the arm 28 is provided with arbor portions 31 and 32 of reduced diameter, and abutment plates 33 and 34 are pivotally mounted one on each of these arbors.

Each of these abutment plates is of rectangular cross-sectional shape and has a sleeve formation, as indicated at 35 and 36, respectively, extending thereacross at its mid-length location and rotatably receiving the corresponding arbor on the arm 28.

In attaching this pontoon to a ship or boat hull, suitable eyes or lugs 37 connected one to each chain at the ends of the chains remote from the lugs 26, are secured to the wall 38 of the boat hull near the bottom of the hull, as is particularly illustrated in Figures 1 and 2.

In the arrangement illustrated there are five chains 21 spaced apart at substantially equal intervals along the corresponding channel member of the reinforcing structure 47, but it is to be understood that this number may be varied to suit different operating conditions without in any way exceeding the scope of the invention.

When the lugs 37 have been attached to the wall of the boat hull, a vertically elongated slot 39 is provided in the hull wall above the center lug. At this point in the attachment the valve 16 is closed and sufficient air is supplied to the interior of the hollow body from a compressed air hose to cause the body to swing to a substantially upright position, as illustrated in Figures 1 and 2. As the body swings to its upright position, the pointed end 26 of the bar 23 is placed in the slot 39, and the abutment plates 33 and 34 are brought to bear against the outer side of the hull wall adjacent the slot in this wall.

A suitable number of the bell-type pontoons are connected to the outside of the submerged hull in the manner indicated above, and all brought to upright position, as illustrated in Figure 1 in which they are suspended from the hull by the corresponding chains 21. After all of the pontoons have been attached, additional compressed air is supplied to the interiors of all of the pontoons, preferably simultaneously, causing the pontoons to rise from the position illustrated in Figure 1 to that illustrated in Figure 2 in which

the chains 21 are upwardly tensioned. The application of compressed air to the interior of the pontoon is continued until sufficient lift is obtained to raise the submerged hull. When the pontoons have risen substantially to the surface of the water or to the maximum height at which they will buoyantly support the hull, the hull may either be towed to a predetermined destination, or, if desired, a submergible dry dock may be placed under the hull and the hull then floated in this dry dock to a location where it can be dismantled or repaired.

In the form of the invention illustrated in Figures 6 to 10, inclusive, the hollow body 40 is of substantially circular cross-sectional shape and has an annular side wall 41 of a length materially greater than its maximum diameter and tapering from one end to the other, so that a number of these pontoons can be nested together for convenience in transportation and storage, as particularly illustrated in Figure 11.

The smaller end of the body 40 is closed by a domed end wall 42 having a marginal flange 43 received within the side wall 41 at the smaller end of the side wall and permanently secured to the side wall by welding or other suitable means.

A cable attaching eye 44 is secured to the end wall 42 and projects outwardly from the outer side of the end wall for the attachment of a cable 45 to the pontoon for raising and lowering the pontoon, and a manually controlled valve 46 is secured in the end wall 42 for controlling the flow of air out of the hollow body.

An annular reinforcing structure 47 of channel-shaped cross-section surrounds and is secured to the side wall 41 at the larger end of the body, with its flanges projecting outwardly from the body, and one of its flanges substantially flush with the adjacent edge of the side wall. Apertured lugs 48 are secured to the reinforcing structure 47 at angular intervals therearound, and each of these lugs is disposed substantially perpendicular to the web and to both flanges of the channel-shaped reinforcing structure. In the arrangement illustrated there are four lugs 48 spaced apart at angular intervals of substantially 90°, but the number of lugs used and their spacing may be varied without in any way exceeding the scope of the invention.

This form of the invention also includes an inner reinforcing structure 50 comprising a ring 51 of channel-shaped cross-section, and cross-bars 52 and 53 extending diametrically of the ring 51 at right angles to each other and having their opposite ends secured to the ring.

The inner reinforcing structure 50 is secured in the open end of the hollow body 40 by bolts 54 extending through registering apertures in the ring 51, the side wall 41 and the outer, annular reinforcing structure 47, these bolts being spaced apart at angular intervals around the reinforcing structure 47, as illustrated in Figure 6. Between the bolts 54 the ring 51 of the inner reinforcing structure is provided with tapped holes and set screws 55 are threaded through these holes and bear against the inner side of the side wall 41 to space the inner reinforcing structure circumferentially from the inner surface of the side wall 41 at the open end of the pontoon body 40.

The inner reinforcing structure, when secured in the open end of the body with the set screws 55 properly adjusted, supports the open end of the pontoon body against distortion when subjected to lifting force.

5

Suitable strands, such as the cables 56, are connected one to each of the lugs 48 each at one end thereof, and may be connected at their other ends to an object to be raised, such as that indicated at 57.

When the pontoons are nested, as illustrated in Figure 11, the inner reinforcing structures are removed from all except the bottom pontoon, and these structures may be stacked one upon the other in a space saving arrangement.

It is contemplated that this modified form of pontoon will be used mainly for lifting separate objects, such as spars, anchors and cargo crates or packages, to lighten a submerged hull preliminary to raising the hull, and also to assist the hull raising pontoons when necessary. In using the modified pontoons, the pontoon may be lowered into the water with the valve 46 open, so that the air in the pontoon will escape and the pontoon will sink of its own weight. When the pontoon has been lowered to a location adjacent the object to be raised, the cables 56 are attached to the object and the valve 46 closed. An air hose 58 is then brought to a location adjacent the pontoon and an angularly bent pipe 59 secured to the end of the air hose is inserted into the pontoon and a valve 60 in the pipe opened to admit compressed air to the interior of the pontoon body. The pontoon will first swing to an upright position and, as its compressed air content is increased, will rise in the water carrying the attached object with it.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A bell type pontoon for raising submerged hulls comprising a hollow body having a side wall and an end wall secured to said side wall at one end of the latter and closing the upper end of said body, a reinforcing structure surrounding said body at the lower open end thereof and secured to said side wall, means secured to said reinforcing structure and extending therefrom for connecting the bottom end of said pontoon to a submerged hull, means providing a guideway extending across said end wall medially of the width of the end wall and having an open end disposed above said means for connecting the bottom end of said pontoon to a submerged hull, a bar slidably mounted in said guideway for movements of adjustment longitudinally thereof and projecting at one end outwardly of the side wall of said body, means securing said bar to said end wall at selected extents of projection of said one end of said bar outwardly of said side wall, said one end of said bar being insertable into a slot cut in a submerged hull to which said body is connected, and plate means movably mounted on said bar near said one end of the bar and adapted to bear against a hull into which said one end of the bar is inserted.

2. A bell type pontoon for raising submerged hulls comprising a hollow body having a side wall and an end wall secured to said side wall at one end of the latter and closing the upper end of said body, a reinforcing structure sur-

6

rounding said body at the lower open end thereof and secured to said side wall, means secured to said reinforcing structure and extending therefrom for connecting the bottom end of said pontoon to a submerged hull, means providing a guideway extending across said end wall medially of the width of the end wall and having a open end disposed above said means for connecting the bottom end of said pontoon to a submerged hull, a bar slidably mounted in said guideway for movements of adjustment longitudinally thereof and projecting at one end outwardly of the side wall of said body, means securing said bar to said end wall at selected extents of projection of said one end of said bar outwardly of said side wall, said one end of said bar being insertable into a slot cut in a submerged hull to which said body is connected, and plate means movably mounted on said bar near said one end of the bar and adapted to bear against a hull into which said one end of the bar is inserted, said body being of rectangular cross sectional shape with said one end of said bar projecting from one side thereof, and said means for connecting the bottom end of said pontoon to a submerged hull comprising chains secured to said body at the side thereof from which said bar projects and at locations spaced apart along the bottom edge of said side.

30 3. A bell type pontoon for raising submerged hulls comprising a hollow body having a side wall and an end wall secured to said side wall at one end of the latter and closing the upper end of said body, a reinforcing structure surrounding said body at the lower open end thereof and secured to said side wall, means secured to said reinforcing structure and extending therefrom for connecting the bottom of said pontoon to a submerged hull, means providing a guideway 35 40 extending across said end wall medially of the width of the end wall and having an open end disposed above said means for connecting the bottom end of said pontoon to a submerged hull, a bar slidably mounted in said guideway for movements of adjustment longitudinally thereof and projecting at one end outwardly of the side wall of said body, means securing said bar to said end wall at selected extents of projection of said one end of said bar outwardly of said side wall, 45 50 said one end of said bar being insertable into a slot cut in a submerged hull to which said body is connected, and plate means movably mounted on said bar near said one end of the bar and adapted to bear against a hull into which said one end of the bar is inserted, said plate means 55 60 comprising an arm pivotally mounted intermediate its length on said bar and extending above and below said bar, and plates mounted on said arm one above and one below said bar for turning movements about said arm.
